WELLINGTON PARKER KIDDER, OF BOSTON, MASSACHUSETTS, AND CHARLES W. SPONSEL,
OF HARTFORD, CONNECTICUT, ASSIGNORS TO PARKER MACHINE COMPANY, OF BUFFALO,
NEW YORK, A CORPORATION OF NEW YORK.

TYPE-WRITING MACHINE.

No. 879,107.

Specification of Letters Patent.

Patented Feb. 11, 1908.

Application filed May 12, 1906. Serial No. 316,471.

To all whom it may concern:

Be it known that we, WELLINGTON PARKER KIDDER and CHARLES W. SPONSEL, residing at Boston, county of Suffolk, and State of Massachusetts, and Hartford, county of Hartford, and State of Connecticut, respectively, have invented certain new and useful Improvements in Type-Writing Machines, of which the following is a full, clear, and exact 10 description, such as will enable others skilled in the art to which it appertains to make and use the same.

Our invention relates to typewriting machines, and has for its main object to provide 15 means for rendering the platen immovable from the printing plane under pressure of the printing instrumentalities.

Another object is to provide means for holding the platen in a fixed position during 20 printing, yet such that the platen may be accurately adjusted to or from the printing plane and held immovably in any adjusted position.

A further object is to provide platen-supporting means of exceedingly light and simple construction, through the employment of which the platen-supporting framework of existing machines may be substantially eliminated.

30 Other objects will be in part obvious and in part pointed out hereinafter.

The invention accordingly consists in the features of construction, combinations of elements and arrangement of parts hereinafter 35 set forth and the scope of the application of which will be indicated in the following claims.

In the accompanying drawings, wherein is illustrated two of the various possible embodiments of our invention, Figure 1 is a transverse sectional view thereof showing certain of the parts in elevation. Fig. 2 is a longitudinal sectional view taken on line a—a of Fig. 1. Fig. 3 is a view in elevation, showing the means employed to indicate the position of the platen with respect to the printing plane. Fig. 4 is a top plan view of a portion of the machine, showing certain features of our invention. Fig. 5 is a longitudinal 50 sectional view taken through a typewriting machine showing a different embodiment of our invention.

Similar reference characters refer to simi-

lar parts throughout the several views of the drawings.

In order that the more important objects and advantages of our invention may be understood, it may be noted that the writing machine to which our invention is especially adapted comprises a type known as "silent 60 type-writers", wherein the printing characters press against the impression surface in contradistinction to the usual types which effect printing by impact or concussion of the printing characters. It is desirable in this 65 type of machine that a substantially rigid impression surface be provided, as any movement of the platen under pressure of the printing device seriously affects the quality of the work, and especially is this true where 70 considerable pressure is exerted to produce a large number of copies, as in manifolding. It is, moreover, desirable that the platen be capable of adjustment toward or from the normal printing plane, which is the common 75 plane occupied by the front faces of the printing characters in their extreme projected position.

By our invention, which we shall presently describe, we preferably attain the above, 80 among other ends, by anchoring a tie-rod in the front rigid framework of the machine and extending the same transversely thereof to the rear of the platen behind the printing point thereof, to provide a rigid abutment 85 therefor, leaving the rear portion of the machine substantially free from supporting framework. We also provide means operable from a convenient location for shortening or lengthening the effective length of this 90 tie-rod, enabling the operator at will to cause the platen to advance or recede from the normal printing plane, the amount of movement thereof in either direction being indicated by a suitable device preferably visible 95 at all times to the operator.

The above and other advantages are secured in constructions of the nature of that hereinafter described.

Referring now to the drawings, and particularly to the embodiment shown in Figs. 1 to 4 inclusive, 1 indicates the framework of the machine, carrying a bed 2 suitably supported upon the side walls thereof, across which type-bars 3, but one of which is shown, 105 are projected, said type-bars, in the present

instance, being shown provided with a plurality of printing characters. Type-bar 3 is connected by means of link 4, toggle mechanism 5 and rod 6 to key-lever 7, which rests upon universal bar 8. The above mechanism, however, forms no essential part of our present invention, but serves as an aid, merely, in rendering the same clearer of understanding.

10 At the rear of the machine, supported by standards 9, is a stationary rail 10, upon which rides a tubular slotted yoke 11, comprising a portion of the carriage, said yoke being carried upon grooved wheels or casters 12, which extend through openings 13 in the yoke and run upon rail 10. Yoke 11 is afforded feed for letter-spacing through rack 14 and pinion 15, by suitable escapement devices, not, shown. Rigidly mounted upon yoke 11 at either end thereof, and extending upwardly therefrom, are channeled guides 16, which operate through means hereinafter described to guide the platen when the same is shifted for upper or lower case printing, 25 said platen frame being shifted to different printing positions by means of shift mechanism operating through channel-bar 18, which extends longitudinally of the carriage.

Near the upper extremity of the side members 19 and 20 of the platen-frame 17 is journaled a paper roll 21, having an operating handle or knob 22. Side members 19 and 20 also form a support for a longitudinally-extending I-beam rail 23, which has, at either end thereof, parallelly-arranged side arms 24 and 25 extending forwardly therefrom and supporting at their forward ends, in the present instance by means of screws 26, the platen 27. Platen 27 is comprised by a thin strip of metal having a plane impression face 28, and has its rear face 29 curved to rest against the curved periphery of paper roll 21 so as to fit the same closely. I-beam rail 23 is substantially co-extensive with the length 45 of platen 27 and slides, when feeding of the carriage is afforded for letter-spacing, in a block 30, provided with lips 31 and 32, which take about the edge of said I-beam rail 23 and maintain the block in close engagement 50 with I-beam rail 23 but allow said I-beam rail to freely slide therebetween when the carriage is fed for letter-spacing.

In order that the platen may be rendered unyielding against pressure of the printing characters, we have provided a tie-rod or bar 33 extending transversely of the machine in the central portion thereof, which is supported intermediate its length in a guiding trough 34 depending from bed 2 and suspended therefrom by suitable means as, in the present instance, by screws 35. Tie-rod 33, which may be thickened as at 36, if desired, to give added strength, has at its rear portion a vertical extension or abutment 37 provided with ways 38 to receive

inwardly-extending lips 39 of block 30, said tie-rod 33 extending forwardly through a support or hanger 40 depending from bed 2 and receiving in a threaded opening 41 in the forward end thereof an adjusting screw 42 70 extending through an opening 43 in the rigid front wall 44 of the framework of the machine, screw 42 being prevented from endwise movement by means of collars 45 and 46 pinned thereto at 47 and 48 respectively. 75 Collar 45 is provided with a handle 49 by means of which adjusting screw 42 may be turned, and a pointer 50 registering upon a concentrically arranged scale 51. Depending from bed 2 is a rigid curved member or 80 lug 52 from which extend radial braces 53 joining the bed with the front wall 44 of the framework of the machine. By means of these braces, the wall of the framework is held rigid against all stresses exerted by the 85 tie-rod. Resting against member 52 and entering opening 54 in the end of tie-rod 33 are strong coil springs 55, one of which is arranged at either side of adjusting screw 42. These springs exerting their influence against 90 the end of tie-rod 33, take up any lost motion in the tie-rod and at all times compel abutment 37 to assume the rearmost position permitted by the adjustment of screw 42. It should, however, be noted that as 95 screw 42 is fixed by washers 45 and 46 against endwise movement and screw 42 being threaded into the end opening of tie-rod 33, very little lost motion, if any, can ever exist in the tie-rod. A paper table 56 is supported upon the inner beveled edge of I-beam rail 23 and extends about the under surface of paper roll 21.

From the foregoing description of the above described embodiment of our invention, it will be observed that platen 27 is carried at either end by rigid member extending forwardly from opposite ends of I-beam rail 23, and for substantially its entire length 105 rests in contact with paper roll 21, the journals of which extend through side members 19 and 20 of platen frame 17, and, as, I-beam rail 23 rests against block 20 interposed between the same and abutment 37 of tie-rod 33, any pressure upon the platen will produce a direct pull upon the tie-rod. This tie-rod being rigidly anchored against endwise movement by reason of its attachment to the front wall of the framework, the platen is prevented from yielding under pressure of the printing devices. Block 30, sliding in ways 38, permits the platen to be shifted from normal printing position to other printing positions, and I-beam 23, in turn, slides in block 30 when letter-spacing is afforded. 110 When it is desired to adjust the platen with respect to the normal printing plane, such adjustment may be effected by simply turning adjusting screw 42 of tie-rod 33 by means of operating handle 49, the amount of the 115 120 125 130

receding or advancing movement thereof being accurately measured and indicated upon scale 51. It will be noted that tie-rod 33 takes the place of the supporting framework usually employed in type-writing machines, leaving the rear portion of the machine entirely free for the attachment of tabulating or other auxiliary devices, which, if desired, may be supported from the tie-rod. The tie-rod, while substantially rigid against yielding due to endwise or tensile stress, is nevertheless of exceedingly light construction, which fact materially lessens the weight of the machine.

In Fig. 5 we have shown an adaptation of our invention differing slightly from the one above described, in that the platen frame is rigidly yet slidably anchored in a yoke adjustably connected with the rear end of the tie-rod. In this embodiment, as in the embodiment above described, the platen frame 17 is mounted for shifting in vertically disposed channeled guides 16 and has, at either end, upwardly extending arms 57, which form journals for the shaft of the paper roll 21. Forwardly from arms 57 extend arms 58, between which is extended the platen 27, said platen being constructed similarly to that in the embodiment above-described and lying against the periphery of the paper roll in a similar manner. Upon an upright 59 erected upon channel bar 18 of the platen frame, disposed between the side walls thereof and rigidly connected therewith, is a rail or plate 60 provided at its forward portion with a downwardly turned flange 61. This flange extends the entire length of the rail or plate 60, and is slidably fitted in a channeled block 62, which has an upwardly turned lip 63 for engaging the rear surface of flange 61. Block 62 is provided in its forward portion with a channeled way 64, the walls of which take about a flange 65 of a yoke 66 slidably supported but fitting closely between the walls of a guiding trough or channeled bracket 67 depending from the type bed. Legs 68 of yoke 66 extend forwardly and approach each other to unite in an integral internally threaded member 69 which engages the threaded end of a tie-rod 70 suitably supported for sliding in hangers 71 depending from type bed. This tie-rod extends through the front wall of the machine and has rigidly secured thereto a knob 75 or operating handle 72, preferably milled as shown, said milled knob carrying a pointer 73 which registers on a suitable scale provided on the front wall of the machine as in the embodiment first above described. In this embodiment of our invention we have shown a tiltable paper table 74 which is journaled at 75 upon lugs 76 extending from plate 60, said table being provided at its forward end with a presser roll 77 held yieldably against the paper roll by suitable springs not

shown herein as the same comprises no essential part of our present invention. In the operation of this embodiment of our invention it will be understood that when feed of the carriage is afforded by the escapement mechanism, flange 61 of plate 60 will slide in block 62 and that block 62 will ride on flange 65 of yoke 66 when the platen frame is shifted for different case printing. When it is desired to adjust the platen with respect to the normal printing plane, such adjustment may be accomplished by turning the tie-rod by means of operating handle 72, the position of said platen with respect to such printing plane being indicated upon the scale provided upon the front wall of the frame of the machine as in the embodiment first above described. The platen, through arms 57, plate 60, and block 62, which is connected to the yoke of the tie-rod, is held rigidly against rearward movement under pressure of the printing instrumentalities when projected thereagainst.

It will accordingly be seen that we have provided constructions well adapted to attain the ends and objects of our invention, some of which have been already pointed out which will operate with a high degree of efficiency. An important advantage secured by the structures as thus described resides in the fact that through the adjustable character of the platen with respect to the printing point the printing characters may be applied to the impression surface with any desired degree of pressure, thus securing even impressions through the employment of inking ribbons in various stages of wear, or of ribbons impregnated with different quantities of ink. The adjustment of the platen can be easily and quickly accomplished from a location near the key-board convenient to the operator, and the co-operating scale and pointer mechanism at all times indicates its exact position. It should further be noted that since the tie-rod is anchored in the front wall of the framing of the machine near the pivotal supports of the type-bar projecting means, and whether extended rearwardly of the platen or furnishing an anchor for the platen beneath the same, it forms a rigid abutment for the said platen, and not only resists pressure of the type-bars exerted thereagainst, but, as well, resists the reaction of said type-bars communicated to the front wall of the machine through their projecting devices. It should also be noted that the tie-rod furnishes a tension member which connects the framing of the machine and the support of the type-bar actuating mechanism with the platen.

It will, of course, be apparent that while both embodiments of our invention, as herein shown and described, are especially adapted for the type of machine with which they are shown associated, they are also well

adapted for use with other forms of typewriting machines.

As many changes could be made in the above constructions and many apparently 5 widely different embodiments of our invention could be made without departing from the scope thereof, we intend that all matter contained in the above description or shown in the accompanying drawings shall be interpreted as illustrative and not in a limiting sense. We desire it also to be understood that the language used in the following claims is intended to cover all of the generic and specific features of the invention herein described and all statements of the scope of the invention which, as a matter of language, might be said to fall therebetween.

Having described our invention, what we claim as new and desire to secure by Letters 20 Patent is:—

1. The combination, in a typewriting machine, of a platen tied against pressure of the type bars by means anchored in the framing of the machine intermediate its ends and extending rearwardly to a point behind the platen.

2. The combination, in a typewriting machine, of a platen tied against pressure of the type bars by means anchored in the framing 30 of the machine and extending transversely thereof intermediate its ends, the pressure resisting portion thereof being in line with the printing point.

3. The combination with the platen of a typewriting machine, of means which extends transversely of the machine in the central portion thereof for tying the platen to the front of the framework of the machine so that movement thereof is prevented, while 40 the printing characters are being impressed against the platen.

4. The combination with the platen of a typewriting machine, of means extending from behind the printing point on the platen 45 and then through the central portion of the machine to the front portion thereof, said means being anchored in the framing of the machine whereby thrusts of the type bars are effectively resisted.

5. In a typewriting machine, the combination of a platen, and pressure-resisting means located directly behind the printing point thereof, said means extending transversely through the central portion of the machine 55 and being anchored to the front portion of the frame of the machine whereby the platen is rendered immovable in the direction of the thrusts of the printing devices.

6. In a typewriting machine, the combination of a platen, and a rod anchored at one end in the framework of the machine, extending transversely thereof, and having its opposite end connected with the platen behind the printing point so as to furnish a backing for 60 the platen which is stationary during printing.

7. The combination, in a typewriting machine, of a platen, and a device comprising a pair of connected, relatively adjustable members, one end of which furnishes a backing for the platen and having the opposite end thereof anchored in the frame of the machine, said device operating to maintain the platen against movement from the printing plane under pressure of the printing instrumentalities. 70

8. In a typewriting machine, the combination with the platen, a device comprising a pair of relatively adjustable members one end of which furnishes a backing for the platen and having the opposite end thereof anchored in the frame of the machine, said device operating to maintain the platen against movement during printing, and means for adjusting said members relatively 80 to each other.

9. The combination with the platen of a typewriting machine, of a rod anchored in the front of the framing of the machine and extending rearwardly intermediate the ends 90 of the machine to a point behind the printing point of the platen to furnish a rigid backing for the platen while printing is being effected.

10. In a typewriting machine, in combination with the printing devices and the platen, of means for furnishing a rigid backing for the platen through a connection with a rigid part of the framework in the front portion of the machine intermediate the ends thereof. 95

11. In a typewriting machine, in combination, a platen, and adjustable means extending rearwardly from a rigid part of the machine in the front portion intermediate the ends thereof that effectively prevents yielding of the platen under the pressure of the type bars. 100

12. In a typewriting machine, in combination, a platen, and means extending rearwardly from a rigid part of the front of the framing of the machine and then extending upwardly to a point directly behind the printing point of the platen to furnish a rigid 110 backing therefor.

13. In a typewriting machine, in combination, a platen, and means for tying the platen to the central portion of the front wall of the framing of the machine. 115

14. In a typewriting machine, in combination, a platen, means for tying the platen to the front wall of the framing of the machine intermediate the ends thereof, and means for changing the length of said tying means. 120

15. In a typewriting machine, in combination, a platen, and extensible means extending rearwardly from the front portion of the frame of the machine intermediate its ends to a point behind the platen to form an immovable support therefor. 125

16. In a typewriting machine, in combination, a platen, means for adjusting the platen in the direction of the stroke of the type bars, 130

- 5 said adjusting means being operable from a position in the front of the machine near the keyboard, and means coöperating with said adjusting means to indicate the amount of adjustment given the platen.
- 10 17. In a typewriting machine, in combination, a platen, and means located at the front portion of the machine near the keyboard for adjusting the platen toward or from the printing plane, said adjusting means operating to maintain the platen against yielding in any adjusted position.
- 15 18. In a typewriting machine, in combination, a platen, adjusting means for the same anchored in the front wall of the machine, and means for operating said adjusting means whereby the platen may be moved toward or from the printing plane.
- 20 19. In a typewriting machine, in combination, a platen, adjusting means therefor anchored in the front wall of the machine, and means coöperating with said adjusting means to indicate the amount of adjustment given the platen thereby.
- 25 20. In a typewriting machine, in combination, a platen, a member forming a rigid abutment therefor extending forwardly thereof, and a screw-threaded member anchored in the front wall of the machine and coöperating with said first-mentioned member to move said platen toward or from the printing plane.
- 30 21. In a typewriting machine, in combination, a platen, an unyielding abutment for the platen extending forwardly thereof, a member having a threaded connection with said abutment anchored in the front wall of the machine, means for rotating said member to cause said abutment to move the platen toward or from the printing plane, and means for indicating the amount of rotation given said rotating means.
- 35 22. In a typewriting machine, the combination with the carriage, of a platen frame forming a part thereof, and movably mounted therein, a platen rigidly supported in the platen frame, and rigid backing means for the platen frame extending forwardly thereof attached to the front wall of the framework of the machine.
- 40 23. In a typewriting machine, in combination, a platen, means for supporting the platen at either end thereof, and an abutment adapted to prevent yielding of the platen supporting means when the platen is engaged by the printing instrumentalities, said abutment being held in a rigid position by means extending transversely of the machine, intermediate the ends thereof, and attached to a fixed part of the machine.
- 45 24. In a typewriting machine, in combination, a platen, means for supporting the platen at either end thereof, an abutment adapted to prevent yielding of the platen supporting means when the printing instrumentalities are projected to impression, and means anchored in the front wall of the frame of the machine intermediate the ends thereof and connected with said abutment adapted to hold the same against movement.
- 50 25. In a typewriting machine, in combination, a platen, a support for the platen, and a tie rod for the platen support, one end of which furnishes a rigid abutment for the platen support behind the printing point of the platen, the opposite end thereof being anchored in the front wall of the typewriter frame intermediate the ends thereof.
- 55 26. In a typewriting machine, in combination, a platen, means for supporting the platen at either end thereof, an abutment located behind the printing point of the platen adapted to prevent yielding of the platen-supporting means when the platen is engaged by the printing instrumentalities, means connected with a rigid portion of the typewriting machine for holding said abutment in a stationary position, and means interposed between the platen-supporting means and said abutment adapted to permit the platen to be shifted to other printing positions or to be fed for letter spacing.
- 60 27. In a typewriting machine, in combination, a platen, means for supporting the platen, means located directly behind the printing point of the platen adapted to furnish a rigid abutment for the platen-supporting means, and means interposed between said platen-supporting means and said abutment which permits the platen to be shifted for different case printing or to partake of letter-spacing movement.
- 65 28. In a typewriting machine, in combination, a platen, a support for the platen, and a tie rod for the platen support, one end of which furnishes a rigid abutment for the platen support behind the printing point, the opposite end thereof being anchored in the front wall of the machine, and means interposed between the platen support and said last-mentioned means adapted to allow shifting of the platen to another printing position or to partake of a letter-spacing movement.
- 70 29. In a typewriting machine, in combination, a platen, a platen support, a rigid abutment for the platen support, and means interposed between said platen support and said abutment adapted to slide upon said abutment when the platen is shifted to another printing position, said platen support being adapted to slide in said last-mentioned means when letter-spacing movement is afforded.
- 75 30. In a typewriting machine, in combination, a platen, a platen support, a rigid abutment for the platen support, and a block slidably mounted upon said abutment and

- 6
- interposed between the same and said platen support in which block said platen support is slidably mounted.
31. In a typewriting machine, in combination, a platen, a platen support, a rigid abutment for the platen support, and a loosely-mounted block carried by said platen support sliding in ways in said abutment when the platen is shifted to other printing positions.
- 10 32. In a typewriting machine, in combination, a platen, a platen support, a rigid abutment for the platen support, and a block in which the platen support slides when letter-spacing movement is afforded, said block sliding relatively to said abutment when the platen is shifted to another printing position.
- 15 33. In a typewriting machine, in combination, a platen, a platen support, an abutment forming a rigid backing for the platen support, and a block interposed between said platen support and said abutment provided with means loosely engaging said platen support to permit a letter-spacing movement thereof and being further provided with means sliding in ways in said abutment when the platen is shifted to other printing positions.
- 20 34. In a typewriting machine, in combination, a platen frame comprised by a pair of side members joined by a rigid, longitudinally-extending member, a platen supported by extensions from the ends of said last-mentioned member, a paper roll journaled between said side members of the platen frame, the periphery thereof forming a rigid backing for said platen intermediate the ends thereof, a block in which said longitudinally-extending member slides when the platen frame is fed for letter-spacing, and a rigid abutment in which said block slides when the platen frame is shifted to other printing positions.
- 25 35. In a typewriting machine, in combination, a platen frame comprised by a pair of side members joined by a rigid cross member which extends longitudinally of the machine, a platen supported by means extending forwardly from the ends of said cross member, a paper roll journaled in the side members of said platen frame at or near the intersection of said side members of the platen frame with said platen-supporting means, the periphery of said paper roll conforming to the rear surface of said platen and forming a backing therefor, a block provided with a way in which said cross member slides when the platen frame is fed for letter-spacing, and a rigid abutment provided with ways in which said block slides when the platen frame is shifted to other printing positions.
- 30 36. In a typewriting machine, in combination, a platen frame comprised by a pair of side members joined by a rigid cross member which extends longitudinally of the machine, forward extensions from said cross member,
- a platen rigidly connected to said forward extensions, a paper roll journaled at substantially the intersection of the side members of said platen frame and said forward extensions, a block provided with a way in which 70 said cross member slides when the platen frame is fed for letter-spacing, an abutment provided with ways in which said block slides when the carriage is shifted to a different printing position, and means connecting 75 said abutment with the front wall of the machine.
37. The combination in a typewriting machine, of means for effectively resisting pressure of the printing instrumentalities comprising a platen, a paper roll against which the platen rests intermediate its ends, a rigid member upon the forward end extensions of which are carried said platen and said paper roll, and an abutment, behind the printing 80 point of the platen.
38. The combination in a typewriting machine, of means for effectively resisting the pressure of the type bars comprising a member anchored in the front wall of the machine 85 and extending rearwardly thereof to form an abutment, a block slidably mounted upon said abutment, a member sliding in said block, a paper roll carried by forward extensions of said member, a platen also carried by 90 said forward extensions and resting against said paper roll, said platen, paper roll and abutment being arranged in line with the direction of thrust of the type-bars and in a plane parallel to the rearwardly extending 95 member which forms the abutment.
39. In a typewriting machine, the combination with the platen, of a member extending rearwardly from the front wall of the machine to form an abutment for said platen, 100 and supporting means for said member intermediate the ends thereof.
40. The combination with the platen of a typewriting machine, of an abutment, a member extending from said abutment 105 through the front wall of the machine, means for holding said member against endwise movement, and guiding members for said abutment intermediate the ends thereof.
41. The combination with the platen and type bars, of a bed for supporting said type bars, a tie rod anchored in the front wall of the machine and extending rearwardly therefrom and thence upwardly to form an abutment for the platen support, and means depending from said bed through which said tie rod extends.
42. In a typewriting machine, in combination, a platen, a shiftable frame to which said platen is rigidly secured, a rigid abutment for the platen frame adapted to maintain the same against yielding under pressure of the printing instrumentalities against the platen, and means for connecting said abutment to a rigid part of the framing of the 115 120 125 130

front wall of the machine intermediate the ends thereof.

43. In a typewriting machine, in combination, a platen, a vertically shiftable frame to which the platen is rigidly secured, a vertical abutment for the platen frame, a portion of said abutment extending forwardly beneath the platen to be anchored in the front portion of the machine.

10 44. In a typewriting machine, in combination, a platen, a vertically shiftable frame to which said platen is secured, an abutment for the platen frame against which said platen frame presses when the printing instrumentalities are thrust against the impression surface of the platen, said abutment being provided with an extension projecting forwardly thereof beneath the platen, and means connecting the forward end of said extension with the front wall of the framing of the machine.

15 45. In a typewriting machine, in combination, a platen, a platen frame shiftable vertically to another printing position, a rail forming a backing for the ends of the platen, an abutment forming a backing for said rail, and means connecting said abutment with the front wall of the machine, whereby said abutment is held against yielding under pressure of the printing instrumentalities against the platen.

20 46. In a typewriting machine, in combination, a platen frame, a platen carried thereby and shiftable with said platen frame to other printing positions, a paper roll against which the platen rests journaled in said frame, a rail the ends of which form a backing for said paper roll and the platen, an abutment forming a backing for said rail, said abutment being provided with a forward extension dropping beneath the platen and extending forwardly thereof, and a member anchored in the framing of the machine and threaded to the end of said forward extension.

25 47. In a typewriting machine, in combination, a platen frame comprising upright guiding members to permit of shifting said frame, a rail supported at either end by said guiding members, members extending forwardly from the opposite ends of said rail, a platen supported rigidly upon the forward ends of said last-mentioned members, a paper roll journaled in said guiding members against which the platen rests, the journals of said paper roll extending through the members which extend from either end of said rail, said platen, the journals of said paper roll and the rail being in a horizontal alignment, an abutment backing up said rail behind the printing point of said platen, said abutment being dropped beneath said rail, paper roll and platen and extending forwardly thereof, and a member for tying said abutment to the front wall of the machine.

30 48. The combination with the carriage, of

a vertical, shiftable platen frame mounted therein, a platen rigidly secured between the ends of the members which extend forwardly from opposite sides of said platen frame, a paper roll journaled in said platen frame 70 against which the platen rests, said paper roll forming a backing for the platen intermediate its length, a rail extending longitudinally of said platen frame and secured at its opposite ends thereto, a block in which 75 said rail is adapted to slide when letter-spacing movement of the platen is afforded, an abutment provided with a vertical extension having ways in which said block is adapted to slide when the platen frame is shifted to 80 another printing position, said abutment being provided with an extension dropped beneath the platen and extending forwardly thereof, and a member threaded into the forward end of said extension and anchored 85 in the front wall of the framing of the machine.

49. In a typewriting machine, in combination, a member anchored in the front wall of the machine and extending rearwardly thereof and having a vertical extension at its rear end provided with guiding ways, a block sliding in said ways, a rail adapted to slide in said block, a platen, rigid members extending forwardly from the ends of said rail to 95 the forward ends of which said platen is rigidly secured, and a paper roll journaled between said forward-extending members against which said platen rests intermediate its ends.

100 50. In a typewriting machine, in combination, a platen, means anchored in the framing of the machine and extending transversely thereof adapted to prevent movement of the platen in the direction of pressure of the printing devices, and means for taking up lost motion in said first-mentioned means.

51. The combination, in a typewriting machine, of a platen tied against pressure of the type bars by means anchored in the 110 frame of the machine, and means for taking up lost motion in the tying means.

52. The combination, in a typewriting machine, of a platen, means for anchoring the platen to the frame of the machine to 115 render the same immovable against pressure of the printing instrumentalities, and resilient means for holding the platen in the rearmost position permitted by the anchoring means.

53. The combination, in a typewriting 120 machine, of a platen, a tie rod therefor, and means for taking up lost motion in the tie rod.

54. In a typewriting machine, in combination, a platen, a tie rod for the platen, and 125 means for maintaining the tie rod in an extended condition.

55. In a typewriting machine, in combination, a platen, a rigid abutment for the platen, means for moving said abutment to cause 130

the platen to advance toward the printing plane or recede therefrom, and means for yieldingly opposing the movement of the abutment when the same is advanced toward 5 the printing plane.

56. In a typewriting machine, in combination, a platen, a rigid abutment for the platen, means for moving said abutment to cause the platen to advance toward the 10 printing plane or to recede therefrom, and a spring for yieldingly opposing the advancement of said abutment toward the printing plane.

57. In a typewriting machine, in combination, a platen, a member forming a rigid abutment therefore extending forwardly thereof, and a screw-threaded member anchored in the front wall of the machine and co-operating with said first-mentioned member 20 to move said platen toward or away from the printing plane, and means interposed between said members adapted to take up lost motion therebetween.

58. In a typewriting machine, in combination, a platen, adjusting means for the same anchored in the front wall of the machine, means for changing the length of said adjusting means whereby the platen may be moved toward or from the printing 30 plane, and means for maintaining the platen in the rearmost position permitted by the adjustment of said adjusting means.

59. In a typewriting machine, in combination, a platen, a support for the platen, a 35 tie rod for the platen support one end of which furnishes a rigid abutment for the platen support behind the printing point of the platen, the opposite end thereof being anchored in the front wall of the machine, 40 and a spring for maintaining said tie rod in an extended condition.

60. In a typewriting machine, in combination, a platen, a support for the platen, an abutment for backing up the platen support, said abutment extending forwardly of the platen, an adjusting screw threaded into the forward extension of said abutment and anchored in the front wall of the frame of the machine, and a spring resting against a 50 shoulder upon the frame of the machine and exerting its pressure against the forward extension of said abutment.

61. In a typewriting machine, in combination, a platen, a support for the platen, an 55 abutment against which said platen support rests, said abutment dropping beneath the platen and extending forwardly thereof, an adjusting screw one end of which is anchored in the frame of the machine, the opposite end 60 thereof being threadably connected with the forward extension of said abutment, and a pair of springs resting against a shoulder depending from a rigid portion of the frame of the machine and exerting their pressure

against the end of the forward extension of 65 said abutment to cause the same to assume the rearmost position permitted by the adjustment of said adjusting screw.

62. In a typewriting machine, the combination with the type bars, of a platen shift- 70 able for different case printing and which feeds longitudinally for letter spacing, and an abutment erected behind the platen and in line with the printing point thereof for resisting any tendency of the platen to recede from 75 the printing plane under pressures exerted by the type bars.

63. In a typewriting machine, the combination with type bars adapted to print by pressure in contradistinction to printing by 80 impact or concussion, of a platen movable transversely and longitudinally of the printing point, and an abutment located behind the printing point of the platen and in line therewith which effectively resists a recession of the latter from the common plane assumed by the faces of the type bars when 85 they are projected to the printing point.

64. In a typewriting machine, the combination with the type bars, of a platen shift- 90 able for different case printing and movable longitudinally for letter spacing, an abutment erected behind the platen which effectively resists any tendency of the platen to recede from the printing plane under pressures exerted by the type bars when they are projected to impression, and means combined with said abutment for adjusting the platen toward or from the printing plane. 95

65. In a typewriting machine, the combination with direct thrust type bars, of a platen, said type bars and said platen being mounted for relative transverse and longitudinal movements to permit of different case printing and letter spacing, and an abutment 105 erected in line with and behind the printing point of the platen which prevents a relative receding movement between the type bars and the platen when the former are projected to impression. 110

66. In a typewriting machine, the combination with direct thrust type bars, of a platen, said type bars and said platen being mounted for relative transverse and longitudinal movements to permit of different case 115 printing and letter spacing, an abutment which prevents a relative receding movement between the type bars and the platen with respect to the common plane assumed by the faces of the type bars when they are projected to impression, and means for effecting a relative adjustment between the platen and the type bars with respect to the printing plane.

67. In a typewriting machine, the combination with the type bars and the platen, of a member which extends rearwardly and then upwardly behind the platen to form a rigid 125

backing therefor, and means combined with said backing member for adjusting the platen with respect to the printing plane.

68. In a typewriting machine, the combination with the type bars and the platen, of a member extending rearwardly and then upwardly behind the platen to furnish a rigid backing therefor, whereby the pressure of the types against the platen are effectively resisted, and means for adjusting said backing means toward or from the common plane assumed by the faces of the types when projected to impression, whereby the platen is moved in corresponding directions with respect to said plane.

69. In a typewriting machine, the combination with the type bars and the platen, of means extending upwardly behind the platen to form a rigid backing therefor, whereby the pressures of the type bars when they are projected against the platen are effectively resisted, and means combined with said backing means adapted to move the platen toward or from the printing plane.

70. In a typewriting machine, the combination with the type bars and the platen, of a device secured to a rigid portion of the framing of the machine, which extends upwardly behind the platen to furnish a rigid abutment that will effectively prevent a recession of the platen when the type bars are projected thereagainst, said device having means whereby it may be adjusted to cause the platen to move toward or from the common plane assumed by the faces of the type bars when they are projected to impression.

71. In a typewriting machine, the combination with type bars and the platen, of a device extending rearwardly through the machine intermediate the ends thereof, and having a portion thereof extending upwardly behind the platen to form a rigid abutment therefor, said device having means for adjusting said upwardly extending portion forwardly or rearwardly to move the platen in corresponding directions with respect to the common plane assumed by the faces of the types when the type bars are projected to impression.

72. The combination in a typewriting machine, of a platen and a device comprising a pair of connected relatively adjustable members, said device being anchored to a fixed portion of the machine and having one end thereof arranged to furnish a backing for the platen in line with the printing point which effectively holds the same against movement from the printing plane under pressure of the printing instrumentalities.

73. In a typewriting machine, the combination with the platen, of a plurality of type bars adapted to print by pressure, and means for tying the platen against movement under the pressure of the type bars, said means being anchored in the framing of

the machine and extending rearwardly and then upwardly to a point directly behind the printing point of the platen.

74. In a typewriting machine, in combination, a platen, an abutment extending upwardly behind the platen to furnish a rigid backing therefor, means for tying the abutment to a fixed portion of the framing of the machine, and means for changing the length of said tying means.

75. In a typewriting machine, the combination with the platen and a plurality of printing members adapted to print by pressure, of means operable near the front portion of the machine in proximity to the keyboard for adjusting the platen toward and from the printing plane and for maintaining the platen against yielding in any adjusted position.

76. In a typewriting machine, the combination with the platen and a plurality of printing members adapted to print by pressure, of an abutment arranged behind the platen and adapted to furnish a backing therefor, and means connected with said abutment and operable from a position in proximity to the keyboard for moving said abutment toward or from the common plane assumed by the faces of the types when projected to impression.

77. In a typewriting machine, the combination with the platen and a plurality of printing members adapted to print by pressure in contradistinction to printing by impact or concussion, of an abutment arranged behind the platen which furnishes a backing therefor, adjusting means coöoperating with said abutment for moving the platen toward or from the common plane assumed by the faces of the types when they are projected to impression, and means coöoperating with said adjusting means to indicate the amount of adjustment given the platen.

78. In a typewriting machine, the combination with the platen and a plurality of type bars adapted to print by pressure, of an abutment disposed behind the platen and mounted to slide transversely of the machine, a paper roll arranged between said abutment and the platen, a space being provided between said abutment and the paper roll through which the paper may be inserted, and means coöoperating with said abutment to move the platen and the paper roll toward or from the common plane assumed by the faces of the types when they are projected to impression.

79. In a typewriting machine, the combination with the platen frame, of a platen carried thereby, a platen roll journaled in said frame behind the platen, an abutment arranged to slide transversely of the machine and extending upwardly behind the platen frame to furnish a backing therefor, and means combined with said abutment for adjusting the same toward or from the plane

assumed by the faces of the types when they are projected to impression, whereby the face of the platen with respect to said plane may be regulated.

5. 80. In a typewriting machine, the combination with the platen and a plurality of type bars adapted to print by pressure, of an abutment located directly behind the printing point of the platen which is bodily movable 10 toward or from the common plane assumed by the faces of the type when projected to impression, and means for moving said abutment and for holding the same in a predetermined position.
15. 81. In a typewriting machine, the combination with the platen and a plurality of type bars adapted to print by pressure, of an abutment rising from beneath the platen to a position directly behind the printing point 20 thereof which furnishes a rigid backing for the same, and means for adjusting said abutment to carry the platen toward or from the printing plane.
25. 82. In a typewriting machine, the combination with a platen and a plurality of type bars adapted to print by pressure, of an abutment disposed behind the platen, and a paper roll arranged between said abutment and the platen for receiving paper inserted between 30 the same and said abutment and for feeding the paper upwardly across the face of the platen.
35. 83. In a typewriting machine, the combination with a plurality of type bars adapted to print by pressure, of a bed upon which said type bars are mounted, and across which they are slid when projected to impression, a platen, a paper roll arranged behind the platen, an abutment erected behind the paper 40 roll for resisting any tendency of the platen to recede from the printing plane under pressure of the type bars, and a member connected with said abutment and extending forwardly through the front wall of the machine, adapted to adjust the same, whereby the face of the platen may be moved toward or from the printing plane.
45. 84. In a typewriting machine, the combination with a plurality of type bars adapted to print by pressure, of a bed upon which said type bars are mounted, and across which they are slid when projected to impression, a platen, a paper roll arranged behind the platen, an abutment erected behind the paper

55 roll for resisting any tendency of the platen to recede from the printing plane under pressure of the type bars, a member connected with said abutment and extending forwardly through the front wall of the machine, adapted to adjust the same, whereby the face of the platen may be moved toward or from the printing plane, a dial arranged upon the front wall of the machine near the keyboard, and means coöperating with said dial for indicating the amount of adjustment given the 60 platen.

65. 85. In a typewriting machine, the combination with the platen and a plurality of type bars adapted to print by pressure, of actuating mechanism for the type bars, and a tension member extended between the support of said actuating mechanism and the platen.

70. 86. In a typewriting machine, the combination with the platen and a plurality of type bars adapted to print by pressure, of an abutment disposed behind the platen and a tension member extended between said abutment and a fixed portion of the framing of the machine.

75. 87. In a typewriting machine, the combination with the platen and a plurality of type bars adapted to effect printing by pressure, of a movable abutment disposed behind the platen and an adjustable tension member 80 connecting said abutment with a fixed portion of the framing of the machine and for moving the same toward or from the printing plane and for holding it in any adjusted position.

80. 88. In a typewriting machine, the combination with the platen and printing mechanism of a tension member adjustable in the direction of its length and extending between the platen and the support for the printing mechanism.

In witness whereof we affix our signatures in the presence of two witnesses.

WELLINGTON PARKER KIDDER.
